HOSIERY INSPECTING MACHINE
ATTACHMENT

Edward R. Ammon, Reading, Pa.

Application September 11, 1941, Serial No. 410,486

9 Claims. (Cl. 223—77)

This invention is directed to improvements in hosiery inspecting machines including a supporting form upon which stockings are placed to examine the same for defects in fabric, seaming or looping. Instances of such machines are found in my various prior patents, including No. 1,727,499, granted September 10, 1929, No. 2,010,172, granted August 6, 1935, No. 2,023,946, granted December 10, 1935, and No. 2,090,883, granted August 24, 1937.

The primary object of the present invention is to facilitate the examination of areas of a stocking supported on a form which, because of their location, are difficult of examination. The use of mirrors is desirable for this purpose to enable the inspector to easily see areas of a stocking which are hidden from direct vision when the inspector occupies her usual position opposite the side of the stocking form. However, it is difficult to locate a mirror device in a position suitable for viewing hidden areas of a stocking at some portions of the inspecting form without interfering with the application of stockings to the form and their withdrawal therefrom.

It is an important object of the present invention to overcome the problem just referred to. The most difficult area to inspect is the toe portion of the stocking which is supported at the end of the form at which the stockings are applied and removed. It is a specific object of the invention to provide a mirror device in conjunction with the inspecting form which will enable this area of stockings to be examined easily and quickly by the inspector, and to accomplish this in such manner that the mirror device will not be in the way of the operator when stockings are applied to and removed from the form.

The above and other objects are accomplished by providing a mirror device with a movable mounting so arranged that the mirror device during inspection will be located in a viewing position proximate the form from which it is withdrawn to a retracted position during the times when stockings are being drawn on or off the form. In order that the operation of the mirror device may not be imposed as a burden on the inspector, it is further proposed that the same shall be shifted between its retracted and viewing positions automatically. This can be accomplished conveniently in connection with the usual expandible type of form by shifting the mirror device through the actuating mechanism, usually a motor, through which the stocking stretching parts of the form are expanded.

The invention will be understood by reference

to the illustrative drawings and the following detailed description of a preferred embodiment. In the drawings:

Fig. 1 is a front elevation of a hosiery inspecting machine embodying the present invention in conjunction therewith;

Fig. 2 is a top plan view of the machine shown in Fig. 1;

Fig. 3 is a fragmentary front elevation on an enlarged scale of certain parts shown in Fig. 1;

Fig. 4 is a top plan view corresponding to Fig. 3;

Fig. 5 is a fragmentary transverse section taken on line 5—5 of Fig. 4; and

15 Figs. 6 and 7 are diagrammatic views of the front end of an inspection form with a stocking thereon, and respectively illustrating the position of the mirror device at different stages of the inspecting operation.

20 The illustrative hosiery inspecting machine shown in Figs. 1 and 2 includes a supporting table structure 10 having secured to and outstanding from the front thereof near its right end a bracket member 11. The hosiery inspecting form

25 12 is mounted on the bracket in a generally horizontal position, preferably with its left end inclining slightly upwardly. The form is preferably capable of partial rotation on the bracket.

The form includes a plurality of relatively 30 movable stocking stretching parts mounted for projection outwardly from the body of the form as shown and described in greater detail in the prior patents above mentioned. Arranged circumferentially of the right end of the form are

35 a series of welt stretchers 13, calf stretcher 14, heel stretcher 15, and toe stretchers 16. In order that the heel stretcher may be properly positioned to receive the heel pocket of stockings of different foot size, the toe supporting portion 17

40 embodying the toe stretcher 16 is made separate from and mounted for adjustment lengthwise of the body of the form 12 as more fully explained in Patent No. 2,090,883.

The various stretching parts are expanded by 45 an actuating rod 18 located axially of the form through suitable cam or other operating elements which need not be dealt with here. A compressed air motor 19 controlled by a valve mechanism 20 and operating through connecting rod 21 and

50 cross arm 22 between rod 21 and rod 18 is provided to give power operation of the stocking stretching parts of the form. Motor control valve 20 may be actuated through a foot pedal 23 to supply air to and exhaust air from the motor, or other control means may be employed, as for

example, a control member disposed at the right end of the form to be actuatable by the hand of the inspector incident to manipulation of a stocking, which control mechanism forms the subject-matter of my copending application Serial No. 402,824, filed July 17, 1941.

The mirror device to be used in conjunction with the inspecting machine as above described is movable in character so that it may be shifted from one position to another in the course of inspection. The greatest use of such arrangement will be in connection with the inspection of the end of the stocking toe and the adjoining areas hidden from the direct view of the inspector occupying a position opposite the front of the table 10. The mechanism shown is adapted for such purpose. Mounted on bracket 24 secured to the front of the left end of the table is a stationary supporting plate or member 25 disposed beneath and in spaced relation to the foot portion of form 12. An auxiliary supporting member 26 is mounted on supporting plate 25 for adjustment thereon in a direction lengthwise of the form for reasons hereafter explained. Plate 25 is provided with a series of slots 27 and 28 in which slide stud bolts 29 and 30 secured to the auxiliary member 26. Spacing washers 31 and 32 are preferably applied to the bolts intermediate plates 25 and 26. Plate 26 at its upper side is provided with a series of rack teeth 33 co-active with a locking finger 34 carried by member 35 pivotally mounted on the upper side of plate 25 as best shown in Figs. 3, 4 and 5. Through such arrangement plate 26 may be locked in a number of different positions lengthwise of plate 25.

The auxiliary plate 26 is provided with an elongated guide slot or track 37, best shown in Fig. 3, which is more or less arcuate in form and extending progressively upwardly from left to right. The right hand portion of the slot is horizontal or slightly inclined while the slot adjacent its left end is relatively steeply inclined to the horizontal. A mirror supporting carriage 38 is slidably mounted on auxiliary plate 26 through means of stud bolts 39 and 40 riding in slot 37.

The form of the carriage 38 will depend on the type of mirror means to be employed. From experience I have found that a plurality of relatively small slightly concave mirrors capable of independent adjustment are most satisfactory for use in connection with the movable carriage in the inspection of the stocking toe portion both from the standpoint of producing a full view of the surface areas of the toe which lie in different planes and from the standpoint of size. As best shown in Figs. 2 and 4 carriage 38 is provided with transversely extending arms 41, 42. Arm 41 is provided with a socket receiving supporting rod 43 to the outer end of which is secured a relatively small circular mirror 44. A ball and socket connection 45 is provided between the mirror and rod 43 to provide for a swiveling adjustment of the mirror relative thereto, and preferably the mirror is also free to turn on its connection 45. Connection 45 connects with the mirror adjacent its periphery. Through the arrangement just described the mirror is capable of adjustment through a wide range of positions and angles so that it will give a satisfactory view of the particular toe area of the stocking which it is intended to show to the operator. A second similar mirror 46 is mounted through the same type of adjustable arrangement on the second arm 42 of carriage 48. It will be noted that mirror sup-

porting arm 42 is of somewhat shorter length than arm 41 so that mirror 46 is closer to the axial line of the form than mirror 44. Through this arrangement and the adjustable mounting of the mirrors on plate 25 the end of the stocking toe and the adjoining side areas thereof at the back and undersides of the form toe portion, and also at the forward side of the toe portion, may be clearly viewed by the inspector from her usual position in front of the central side area of the form.

It will be noted that in Figs. 1 and 2 carriage 38 and the mirrors are shown in their retracted right end position wherein the mirrors are located beneath the toe end of the form with a spacing sufficient to enable a stocking to be drawn on the form without interference by the mirrors with the hand of the operator. In Figs. 3 and 4 carriage 38 has been projected to the left beyond the toe end of the form and upwardly towards the axis of the form by its slot track 37 to bring the mirrors into their viewing position beyond and opposite the form toe portion. Shifting of carriage 38 is preferably accomplished automatically so as not to add to the duties of the inspector. This is accomplished through an actuating rod 47 operative through the motor means which effects expansion of the form stretching parts. As best shown in Figs. 1 and 2, rod 21 from motor 19 is provided with a loose collar 48. A pair of fixed collars 49 and 50 are mounted on rod 21 and between such collars and collar 48 are located opposing springs 51 and 52. This provides a lost motion operating connection between rods 21, 47 by which mirror supporting carriage 38 is shifted in its path of movement relative to auxiliary plate 26 despite the greater traverse of actuating rod 21, arm 22 and actuating rod 18 in effecting full expansion of the stocking stretching parts of the form.

As previously mentioned, auxiliary plate 26 together with carriage 38 and the mirrors is adjustable on stationary plate 25 in a direction lengthwise of the form. This is to enable the mirrors to be brought to a correct viewing position for any lengthwise setting of the adjustable form toe section 17 for different size stockings. Because of this adjustability of carriage 38 independently of its shifting movement, it is necessary to make provision for adjusting the effective length of actuating rod 47. This is accomplished as best shown in Figs. 3 and 4 by providing a connecting plate 53 on the left end of rod 47 having a series of notched teeth 54 along its underside which are adapted to interchangeably receive the projecting portion of bolt 40 on the back side of carriage 38. Each time auxiliary plate 26 is adjusted to a new position relative to the stationary supporting plate 25 the connecting plate 53 on actuating rod 47 is adjusted relative to mirror carriage 38.

At the start of an inspecting operation the machine is as shown in Figs. 1 and 2 with the stretching parts of the form collapsed and the mirrors 44 and 46 in their retracted position. The operator draws a stocking on the form. A stocking is shown in position on the form in Fig. 6. The operator then actuates the operating motor 19 through pedal 23 or other control, thus effecting movement of operating rod 21 to the left. This effects expansion of the stretching parts 13, 14, 15 and 16 of the form to stretch the heel, toe and other areas of the stocking. Through rod 47 carriage 38 is shifted to the left and upwardly as previously explained, thereby

throwing the mirrors 44 and 46 into their viewing position as shown in Fig. 7. When the entire stocking has been inspected the operator releases the control causing rod 21 to move to the right. The stretching parts of the form are thus collapsed and mirror carriage 38 moves downwardly and inwardly to its retracted position below the form. The mirrors are now out of the way so that the operator can withdraw the stocking off the form, and thereafter apply a further stocking to the form to begin a new inspection operation.

Through the use of the mirror device of the present invention thorough inspection of the toe area of a stocking can be secured. The operator does not have to shift her position in examining the stocking toe with a consequent saving of effort and time on her part so that her production capacity of inspected stockings is appreciably increased.

It will be understood that the detailed construction herein illustrated and described provides a preferred adaptation of the invention, but that the invention is capable of embodiment in other forms and is to be taken to be protected as broadly as permitted by the scope of the appended claims.

I claim:

1. In a hosiery inspecting machine, a stocking receiving form having movable stocking stretching parts, actuating means for expanding said stretching parts, mirror means for viewing areas of a stocking at a portion of the form obscured from direct vision movable between a viewing position in optical registry with said obscured form portion and a retracted position free from interference with the manipulation of stockings on and off the form, and means for moving the mirror means between retracted and viewing positions in response to operation of the means actuating the stocking stretching parts, whereby the mirror means will be in viewing position when the stocking stretching parts are expanded during periods of stocking inspection, and will be in retracted position when the stocking stretching parts are retracted during periods of manipulation of stockings on and off the form.

2. In a hosiery inspecting machine, a stocking receiving form having a stocking toe supporting end portion and including movable stretching parts for expanding the stocking, actuating means for expanding the stocking stretching form parts, mirror means for viewing the toe area of a stocking on the form movable in a plane parallel to the form axis between a viewing position opposite the toe end of the form and a retracted position laterally offset from the form, and means for moving the mirror means from retracted to viewing position responsive to operation of actuating means for the form stretching parts.

3. In a stocking inspecting machine, a stocking receiving form having a stocking toe supporting end portion and including movable stocking stretching parts, motor means for actuating the stocking stretching form parts, mirror means for viewing the toe area of a stocking on the form shiftable from a retracted position laterally offset from the form to a viewing position opposite the end of the form toe position, means actutable by the motor means which operates the form stretching parts for shifting said mirror means between retracted and viewing positions, a mounting supporting the mirror means for adjustment independently of its shifting movement

to vary its viewing position lengthwise relative to the form, and an adjustable connection for the actuating means between the motor means and the mirror means rendering said actuating means operative to shift the mirror means to different adjusted viewing positions lengthwise of the form.

4. In a hosiery inspecting machine, a stocking receiving form having a stocking toe supporting end portion, mirror means for viewing the toe area of a stocking on the form, a stationary support laterally offset from the form, track means on the stationary support comprising a track portion extending substantially lengthwise of the form and a further track portion in continuation of the first portion inclining towards the form, a movable carriage on the support mounting the mirror means and guided by said track means to shift the mirror means from a retracted position laterally offset from the form to a viewing position opposite the end of the form toe portion, and means for actuating said carriage.

5. In a hosiery inspecting machine, a stocking receiving form having a stocking toe supporting end portion, mirror means for viewing the toe area of a stocking on the form, a stationary support laterally offset from the form, an auxiliary support mounted on the stationary main support, a carriage on the auxiliary support mounting the mirror means and movable on the auxiliary support to shift the mirror means from a position laterally offset from the form to a viewing position opposite the end of the form toe portion, said auxiliary support being adjustably mounted on the stationary main support for movement substantially lengthwise of the form to vary the position of the carriage and mirror means relative to the form, and means for actuating the carriage.

6. In a hosiery inspecting machine, a horizontally mounted stocking receiving form having a stocking toe supporting end portion, a plurality of mirrors arranged transversely of the form and having retracted positions spaced beneath the form toe portion, a stationary support, a carriage mounting the mirrors, means slidably mounting the carriage on the stationary support for movement simultaneously lengthwise of and inwardly towards the form toe portion to shift the mirrors from their retracted positions beneath the form to their viewing positions outwardly of and substantially opposite the end of the form toe portion, means for individually adjusting the mirrors on their carriage, and actuating means for operating the carriage.

7. In a hosiery inspecting machine, a stocking receiving form having a stocking toe supporting end portion, a plurality of mirrors for viewing the toe area of a stocking on the form, a carriage having arms extending transversely of the form, connecting means supporting the mirrors for independent swivel adjustment on said carriage arms, means supporting the mirror carriage for adjustment lengthwise of the form, means for moving the carriage in a plane parallel to the form axis to shift the mirrors between viewing positions opposite the end of the form toe portion and retracted positions removed from the end of the form toe portion.

8. In a hosiery inspecting machine, a stocking receiving form having a stocking toe supporting end portion over which stockings are drawn on and off the form, and including movable stocking stretching parts adapted to expand a stocking for inspection, a support mounting the form,

retractable mirror means for viewing the toe area of a stocking on the form shiftable between a viewing position longitudinally outward of and substantially opposite to the outer extremity of the toe form portion in the path over which stockings are drawn on and off the form and a retracted position in which the mirror means is spaced in laterally offset relation from the form out of the path over which stockings are drawn on and off the form, a stationary supporting member spaced from the form, a shiftable mounting carrying the mirror means, means supporting said mirror mounting means for movement on the stationary member in a fixed path to shift the mirror means alternately between its viewing position and retracted position, and actuating

means for shifting the mounting means in its fixed path and operable to move the mirror means to its viewing position when stockings are in inspecting position on the form and to retracted position during periods between inspection when stockings are drawn on and off the form.

9. A hosiery inspecting machine according to claim 8 and having mirror means comprising a plurality of angularly related mirror surface portions for viewing predetermined areas of the toe of a stocking on the form from different angles, said angularly related mirror portions being supported by the shiftable mounting for simultaneous movement between viewing and retracted 10 positions.

EDWARD R. AMMON.
